PAINTBRUSH HOLDER

Harmon C. Kerby, Indianapolis, Ind., assignor to
Woodrow Skirvin and B. K. Reeves, doing busi-
ness as B & W Manufacturing Company, In-
dianapolis, Ind.

Application November 9, 1946, Serial No. 709,058

1 Claim. (Cl. 220—90)

1

This invention relates to a means for holding a paint brush over and to one side of a paint containing vessel such as the customarily employed can having a friction top closure cap in conjunction with the usual inturned, ribbed flange with which the cap engages.

A primary object of the invention is to provide a brush holder which may be detachably engaged with the paint container whereby the brush holder may be used at those times when the container cap is removed and thereafter the brush holder may be disengaged and the cap returned to its place.

A further primary object of the invention is to provide a brush holder of that type where the brush position will be determined to have the brush in a substantially horizontal position with the bristle ends overhanging the paint container, all in such manner that the bristles will be substantially over the paint vessel whereby the paint residue on the bristles will not come into any appreciable contact with the holder itself, and yet the brush will be supported in a substantial manner.

A further primary object of the invention is to provide a brush holder of the type above indicated wherein paint flowing from the bristles of the brush will be directed back into the paint container rather than being permitted to flow initially into the cap retaining groove around the top of the container.

These and many other objects and advantages of the invention, including the utmost simplicity in structure as well as adaptability to different sizes of brushes, will become apparent to those versed in the art in the following description of one particular form of the invention as illustrated in the accompanying drawing, in which

Fig. 1 is a top plan view of a fragmentary portion of a paint receptacle with a structure embodying the invention applied thereto;

Fig. 2, a vertical section on the line 2—2 in Fig. 1; and

Fig. 3, a view in outside end elevation of the brush holder.

Referring to the drawing, in which like characters of reference indicate like parts in the several views thereof, the invention is intended to be applied to the standard receptacle 10 which is provided with the usual flange 11 around its top end, this flange 11 being so formed as to provide an annular groove 12 therearound to receive the downturned flange of a cap frictionally therein, the cap not being herein shown since it con-

2

stitutes no part of the invention. The structure forming the invention is applied to the can 10 only when the cap is removed.

The brush holder is formed preferably out of some substantially rigid material such as sheet metal to have a substantially flat area 13 generally triangular in shape. From the outer marginal portions of this area 13, the material is carried abruptly upwardly to form the side flanges 14 and 15 respectively. The outer end of this flat area 13 terminates in a straight edge line 16 and the outer ends of the respective flanges 14 and 15 terminate at the outer ends of this line 16. The length of this line 16, which is equivalent to the spacing apart of the outer ends of the flanges 14 and 15 adjacent the area 13, is made to be such that the handle of a paint brush (not shown) will be freely received therebetween but without appreciable side movement.

20 The inner end of this area 13 terminates in an arcuate line 17 conforming in general to the curvature of the flange 11 of the can 10 to which the holder is to be applied. Then the material is bent around and downwardly from the plane 25 of the area 13 by a rounding rib 18 shaped and proportioned to fit down and around the horizontally inturned edge 19 provided at the top of the innermost part of the flange 11. Then in spaced apart relation, the material is carried further downwardly from this rib 18 to form a plurality of separate tongues 20, here shown as three in number, which yieldingly and elastically engage under the lowermost portion of the flange 11 by reason of the foot portions 21 bent therearound from the tongues 20.

Referring to Fig. 1, it is to be noted that the side flanges 14 and 15 diverge one from the other inwardly from the line 16 throughout the major length of the area 13 to merge into the straight length portions 22 and 23 respectively which extend upwardly from the area 13 from parallel base lines therealong and continue to the outer ends of the arcuate line 17. The width of the area 13 between the straight flange portions 22 and 23 is made to be such that the handle body of the brush may be received therebetween without appreciable lateral movement, particularly for the larger sizes of brushes normally employed in painting building structures. In other words, the holder is designed to hold the upper handle portion of the brush, that is that portion into which the bristles are entered and secured, between the flange portions 22 and 23 and to have 50 the handle properly extending therefrom on out

through the opening between the flanges 13 and 14.

The flat portion 13 is provided with upwardly extending members 24 and 25 spaced inwardly from the respective flanges 14, 22 and 15, 23 in substantial parallelism therewith, these members in the present showing constituting ribs upwardly pressed from the material forming the portion 13. The outer ends of these members 24 and 25 terminate substantially in line with the ends of the line 16 at their outer ends, and by their rear ends on a line substantially tangential to the line 17. Then, spaced between the outer end portions of these members 24 and 25 is a central member 26 likewise extending above the level of the area 13 into the plane defined by the tops of the members 24 and 25. In the form herein shown, this member 26 is a rib upwardly pressed from the material forming the area 13. Preferably this member 26 continues by a short length from its outer end so as to leave a major portion of the area 13 free of any obstruction between its inner end and the line 17. By reason of the existence of these members 24, 25, and 26, the brush is held above the portion 13 in spaced relation. This structure not only permits ready draining of paint from under the brush into the can over the rib 18 without entrance into the groove 12, but at the same time, permits the holder to be used on one can after another holding different paint colors without contamination of that different color with the paint on the brush bristles. This is particularly true where paint has been poured from the receptacle 10 over the holder. Since the brush handle proper is supported above the level of the area 13 and extends principally therebeyond, this handle portion does not become coated with paint, and consequently, the operator may keep his hands free of paint. Since the length of the arcuate line 17 is much less than half the circumference of the opening in the can 10, the can may be carried about by the usual bail without having to remove the brush holder.

While the invention has been herein described in reference to the one particular form in minute detail, it is obvious that structural changes may be employed without departing from the spirit of the invention, and I therefore do not

desire to be limited to that precise form beyond the limitations which may be imposed by the following claim,

I claim:

A paint brush holder for use with a paint bucket having an inturned annular flange around its top edge, comprising in combination a planar floor member having an inner, arcuate edge portion conforming substantially to the curvature of the flange on said bucket, said arcuate edge portion extending downwardly over said flange; a plurality of elastic tongues extending below said arcuate edge portion; a foot on each of said tongues turned outwardly to engage the under side of said flange; said floor member having opposite side edge portions extending outwardly from the ends of said arcuate edge portion in parallel relation to each other and then converging inwardly one toward the other to an outer floor terminal transverse edge; flanges turned up from each of said side edge portions; said floor member and said flanges defining an opening at said terminal edge to receive the handle of a paint brush; and a pair of upwardly extending ribs on said floor member spaced inwardly from and substantially parallel to said side edge portions, said floor and edge flanges being proportioned, when a brush is positioned on said floor with its handle extending outwardly through said opening beyond said transverse edge and with the heel of said brush in abutment with the converging side flanges, to have the bristles of said brush overhang the arcuate edge portion and have the brush held against lateral and outward movement over said floor member, and to have the brush held in spaced above relation over said floor by said upwardly extending ribs.

HARMON C. KERBY.
